DESIGN FOR A WOODEN TOY AUTOMOBILE

Kay Bojesen, Copenhagen, Denmark, assignor to Frederik Lunning, Inc., New York, N. Y.

Application September 21, 1939, Serial No. 87,311.

Term of patent 3½ years

To all whom it may concern:

Be it known that I, Kay Bojesen, a subject of the Kingdom of Denmark, residing at Copenhagen, Denmark, have invented a new, original, and ornamental Design for a Wooden Toy Automobile, of which the following is a specification, reference being had to the accompanying drawings, forming part thereof, wherein the figure is a perspective view of a wooden toy automobile showing my new design, the opposite side presenting substantially the same appearance as the side shown.

I claim:

The ornamental design for a wooden toy automobile, substantially as shown and described.

KAY BOJESEN.
